United States Patent Office

Des. 203,684
Patented Feb. 8, 1966

203,684

GAME BOARD

John C. Smith, 320 W. Oakdale, Fort Wayne, Ind.

Filed Jan. 4, 1965, Ser. No. 83,260

Term of patent 3½ years

(Cl. D34—5)

The single figure of the drawing is a perspective view of a game board showing my new design.

I claim:

The ornamental design for a game board, as shown.
